MAGNETIC DEFLECTION SYSTEM PROVIDING PLURAL EXIT PORTS FOR A BEAM OF CHARGED PARTICLES

Stanley Ernest Hunt, Reading, England, assignor to Associated Electrical Industries Limited, London, England, a British company

Filed Feb. 7, 1962, Ser. No. 171,673

Claims priority, application Great Britain Feb. 9, 1961
3 Claims. (Cl. 250—49.5)

This invention relates to deflection systems for deflecting charged particles.

Many accelerators of charged particles (for example Van de Graaff accelerators) are more easily built in a manner which produces a vertical beam of charged particles rather than a horizontal beam, while it is usually more convenient to utilise horizontal beams. There is thus a requirement for a deflection system capable of deflecting the accelerated charged particles through a right angle. One method of producing such a deflection is by means of a magnetic field and hitherto such magnetic deflectors have a single magnet. It is impossible with a single magnetic deflector to ensure that the beam emerging from the deflector is completely parallel sided.

According to the present invention a deflection system for charged particles comprises two or more magnetic deflectors spaced apart from one another and each deflecting the particles in succession so that the total angle of deflection is the sum of the angles through which the particles are deflected in each deflector.

With such an arrangement the distance between the two deflectors can be adjustable to alter the focal length of the system and produce a completely parallel sided emergent beam if required.

In order that the invention may be more fully understood, reference will now be made to the accompanying drawings, FIGURE 1 of which illustrates the invention diagrammatically.

Referring to FIG. 1, it is required to deflect a downwardly extending incident beam 1 through 90° so as to emerge along a horizontal path 2. To achieve this deflection, two magnetic deflectors illustrated diagrammatically at 3 and 4 are provided, each deflector deflecting the beam through 45°. The entry and emergent faces of each deflector are arranged to be normal to the beam. If r is the radius of curvature of the beam through the deflectors, then the two deflectors 3 and 4 are separated by a distance which is adjustable about the value $2r$.

With such an arrangement, the beam deflected in the first deflector 3 becomes focused at a point between the deflectors determined by the momentum of the charged particles and thereafter passes through the second deflector 4 to emerge along path 2. The exact configuration of the beam along path 2, namely, whether it is convergent, parallel sided or divergent, depends on the distance between the two deflectors 3 and 4. In the case of an initially parallel incident beam, if the separation is $2r$, then a completely parallel sided beam is emitted, if the separation is greater than $2r$ a convergent beam is emitted, while if the separation is less than $2r$ a divergent beam is emitted. It should be noted that since the beam is normal to all pole edges, no defocusing takes place in the horizontal plane.

A further advantage of a deflector system according to the invention is that stabilising and control arrangements can be limited to the first of the 45° deflectors only and accordingly will be much less cumbersome and thus much cheaper than where these stabilising or control arrangements are applied to a single deflecting magnet which deflects through 90°.

One example of this is in the provision of a stabilising

2

voltage to control the accelerator which produces beam 1. It will be appreciated that particles emitted by an accelerator are usually of mixed mass, for example, if hydrogen is used as the ion source, the beam will consist of protons, single ionised hydrogen molecules of mass 2 and composite particles of mass 3 consisting of a proton bound to a hydrogen molecule. These particles of different masses are separated by the magnetic field of a deflector since particles of the same charge which have been accelerated through the same potential difference have radii of deflection inversely proportional to the square root of their masses.

In order to prevent attenuation of the beam of particles of wanted mass, say the protons, one or other of the heavier particles can be used to provide the correcting signals to stabilise the voltage of the accelerator.

In the case of the deflector system illustrated, the heavier particles can be made to come to a focus in the space between the two magnets. Thus, if point 5 is the cross-over point of particles of mass 1, particles of mass 2 will focus at a point 6 and particles of mass 3 at a point 7. A suitable exit slit system can be positioned at point 6 or point 7 and the signal therefrom used to stabilise the voltage from the accelerator.

It will be realised that deflector 3 needs to be enlarged to provide focussing of the additional particles but the degree of enlargement of the deflector is much less than the enlargement required to produce the same effect with a deflector of 90°. Thus, there is an overall reduction in cost and weight.

If desired, the field of the second deflector 4 can be stabilised and measured relatively crudely if required. Alternatively, correcting signals can be fed into the current windings of deflector 4 to move the beam slightly relative to a remote target while keeping the energy of the beam accurately stabilised as defined by a stabilised magnetic field in the first deflector 3. Another possibility is to slightly vary the magnetic field of deflector 4 to keep the beam focused on a target irrespective of slight energy fluctuations of the beam allowed by the resolution or stability of the field of deflector 3.

Apparatus in accordance with one embodiment of the invention is illustrated in FIGS. 2 and 3, FIG. 2 being a side elevation, and FIG. 3 a front elevation.

A source of positively charged particles is indicated generally at 10 and an accelerating tube having a plurality of electrodes is shown at 11. The particles pass axially along the tube and a graded potential applied to the electrodes causes the particles to be accelerated, and they enter the deflection system in the form of a beam through a tube 12. The particles enter the system travelling in a vertical plane and, by means of two magnetic deflectors, the particles are deflected through a right angle and leave the system travelling in a horizontal plane. The particles are utilised at a target which is mountable on a target support plate 13.

The deflection system includes two similar electromagnetic deflectors 14 and 14' spaced apart and each arranged to deflect the particles through 45°. Each deflector comprises a pair of shaped pole pieces 15 spaced apart to provide a slit 16, the pole pieces forming part of a magnetic circuit which is capable of carrying a high value of magnetic flux produced in two coils 17. The deflectors are mounted on a support frame 18 and their position relative to the frame and to each other may be adjusted by means of a plurality of adjusting bolts 19. The deflector 14 is arranged on the mounting frame with the slit 16 normal to the axis of the tube 12, and similarly the edge of the slit 16, in the deflector 14', adjacent the target is arranged to lie in a vertical plane. If a parallel sided beam is required at the target, the deflectors 14 and 14' are spaced apart such that the distance between the

output edge of the slit in the deflector 14 and the input edge of the slit in deflector 14', is equal to twice the radius of curvature of the beam through each deflector.

The particles entering the slit formed in the first deflector are of mixed mass, and they are separated by the magnetic field of the deflector since particles of the same charge which have been accelerated through the same potential difference have radii of deflection inversely proportional to the square root of their mass. The lightest particles leaving the deflector 14 enter a beam tube 20 which connects the slits 16 in the two deflectors. These particles are further deflected by the second deflector and finally reach the target. Particles of heavier mass, however, leave the deflector 14 through one or more of the beam tubes 22 as explained hereabove relative to the focusing of particles at points 6 or 7. Each beam tube 22 is terminated by a target holder 23. The particles arriving at the target may be utilised to produce an electrical signal which is fed to the accelerating tube and used to stabilise the voltages applied to the accelerating electrodes.

What I claim is:

1. A deflection system for a beam of charged particles comprising an evacuable vessel, a first port in said vessel through which said beam enters therein, a second port in said vessel through which particles of a given mass and energy egress therefrom, and a path for said particles of given mass and energy between said ports, two similar magnetic deflectors spaced apart along said path, each deflector in succession serving to deflect said particles of given mass and energy through 45° around curved paths of radius r , a mounting frame for supporting said vessel and said deflectors with said deflectors separated by a distance substantially equal to $2r$ and means for moving said deflectors relative to said mounting frame by which 35 the distance between the deflectors may be adjusted.

2. A deflection system for a beam of charged particles comprising an evacuable vessel, a first port in said vessel through which said beam enters therein, a second port in said vessel through which particles of a given mass and energy egress therefrom, a further port in said vessel and a path for said particles of given mass and energy between said ports, two similar magnetic deflectors spaced apart along said path, each deflector in succession serving to deflect said particles of given mass and energy through 45° around curved paths of radius r , said further port being positioned between said deflectors and providing an exit from said vessel for further particles having a mass greater than said particles of given mass, means by which said further particles produce an electrical signal by which means for accelerating said beam prior to it entering the vessel are stabilized, a mounting frame for supporting said vessel and said deflectors with said deflectors separated by a distance substantially equal to $2r$ and means for moving said deflectors relative to said mounting frame by which the distance between the deflector may be adjusted.

3. The combination with a deflection system as claimed in claim 2 of means for producing charged particles, means for forming said charged particles into a beam, a target for utilizing said particles of a given mass and energy which egress from said vessel and means for supporting said target.
